ANIMATED DISPLAY

Ernest O. Estwing, Rockford, Ill., assignor to Estwing Manufacturing Company, Incorporated, Rockford, Ill., a corporation of Illinois

Application August 12, 1954, Serial No. 31,844

Term of patent 14 years

(Cl. D80—1)

Fig. 1 is a front elevational view of an animated display embodying my new design;

Fig. 2 is an end elevational view thereof;

Fig. 3 is a top elevational view thereof; and

Fig. 4 is a fragmentary end elevational view of the end opposite Fig. 2, the balance of this end of the design being a mirror image of Fig. 2.

The dominant features of my design reside in the portions shown in full lines.

I claim:

The ornamental design for an animated display, substantially as shown and described.
